UNITED STATES PATENT OFFICE.

JOHN W. HELTON, OF WATERLOO, IOWA, ASSIGNOR OF FOUR-FIFTHS TO
SAMUEL SHILLIAM, OF WATERLOO, IOWA.

DRAFT-EQUALIZER.

No. 831,432.

Specification of Letters Patent.

Patented Sept. 18, 1906.

Application filed October 30, 1905. Serial No. 285,058.

To all whom it may concern:

Be it known that I, JOHN W. HELTON, a citizen of the United States of America, and a resident of Waterloo, Blackhawk county, 5 Iowa, have invented certain new and useful Improvements in Draft-Equalizers, of which the following is a specification.

My invention relates to draft-equalizers; and the object of my invention is to furnish a 10 detachable and adjustable appliance of the kind mentioned, which will not only remedy any discrepancies in draft, but will have the effect of keeping the vehicle or machine in which it is used constantly in an unfluctuating line of direction. This object I have attained by the means which are hereinafter described and claimed and which are illustrated in the accompanying drawings, in which—

20 Figure 1 is a plan view of an axle with attached tongue having the usual form of doubletree and swingletrees, my equalizing device being shown as connected between said parts in operative position, the ends of the 25 axle being shown as broken away. Fig. 2 is a rear elevation of my equalizing device as detached, while Fig. 3 is a side elevation of the same.

Similar letters refer to similar parts 30 throughout the several views.

An axle *o* is depicted having an attached tongue *p*, to the latter of which a doubletree *n* is pivoted on the wagon-hammer bolt *r*. On the upper surface of the left and right ends of 35 the doubletree *n* is placed a lever *a s* and a lever *a' s'*, respectively, the levers being pivoted to said doubletree at their outer ends by pivot-bolts *c* and *c'*. Hooks *k* and *k'* are fixed in the anterior surface of both ends of 40 the axle *o* to hold the rear ends of the stay-chains *h* and *h'*, respectively, the forward ends of said stay-chains being engaged by hooks *g* and *g'* on the rear ends of the swivels *d* and *d'*, respectively, which latter are at 45 their forward ends pivoted on stubs-bolts *e* and *e'*, fixed to the inner ends of the levers *a s* and *a' s'*. On stub-bolts *f* and *f'*, fixed on the upper and lower levers *a s* and *a' s'*, respectively, are pivoted the swivels *b* and *b'*, 50 said stub-bolts being set intermediately between the bolts *c* and *e* and *c'* and *e'*, respectively, but somewhat nearer the bolts *c* and *c'* to increase the amount of leverage on the inner ends of the levers *a s* and *a' s'*, respec-

tively. The forward ends of the swivels *b* 55 and *b'* are looped into the hooks *l* and *l'* on the swingletrees *m* and *m'*, respectively.

My device is adapted to be used on either vehicles or riding planters or seeders and the like, as in either case it has a beneficial use, as 60 follows: When one horse of the team hitched up to the swingletrees *m* and *m'* slacks back in draft, supposing the horse hitched to the swingletree *m* to do so, the other horse, hitched to the swingletree *m'*, will by superior effort 65 draw forward his end of the doubletree *n* through the medium of the swivel *b'* and lever *a' s'*, with its pivot-bolt *c*. If the connection of the swivel *b'* were direct to the end of the doubletree instead of to an intermediate point 70 of the lever *a' s'*, as shown, the effect would be to throw the tongue *p* over against the other horse and, with the tongue, would move the axle *o* to one side, causing the vehicle to leave the track or vary from a straight line of forward movement. The connecting up of the swivel *b'* to an intermediate point of the lever 75 *a' s'* causes the draft on the end of doubletree *n* to be more gradual, and the interaction of the two sets of levers *a' s'* and *a s* has the effect of 80 causing the axle *o* to keep its position without deflection to either side. Instead of the axle veering about, the doubletree *n* will move pivotally on the bolt *r* without causing the tongue to deflect, thus preventing it from 85 striking the other horse. In the event of a marked tendency or habit of one horse to lag behind the other and cause a slackening in the stay-chain on his side of the vehicle an adjustment can be easily effected by inserting 90 the hook *g* or *g'* into another link of the stay-chain *h* or *h'*, as the case may be, to take up the slack and accommodate the length of the stay-chain to be in the desired position of tautness. 95

The effect in use of my device is to prevent sudden deflections of the axle and the tongue and to keep the vehicle in the same path, obviating almost entirely violent movements thereof to one side, otherwise caused by differences of draft or the encountering of an obstacle, such as a stone, in the track of one of the fore wheels. In the latter event the guidance effected by my device will keep the wheel from wrenching off or being thrown to 100 one side violently when passing over or coming in contact with a stone in the track and will cause the wheel to mount the obstruc- 105

tion quietly and pass over it without inconvenience.

Having described my invention, what I claim as new, and desire to secure by Letters 5 Patent, is—

1. In a draft-equalizer, in combination, a doubletree, swingletrees, an axle, levers pivoted at one end to each end of the doubletree, link connections between said axle and the other 10 ends of said levers, and link connections between said levers and said swingletrees.
2. In a draft-equalizer, in combination, an axle, a tongue attached thereto, a doubletree pivoted to said tongue, swingletrees, levers 15 pivoted at one end to each end of the doubletree, linked connections between said axle and the other end of said levers, and linked connections between said levers and said swingletrees.
3. In a draft-equalizer, in combination, an axle, a tongue attached thereto, a doubletree pivoted to said tongue, swingletrees, levers pivoted at one end to each end of the doubletree, adjustable link connections between 20 said axle and the other end of said levers, and

link connections between said levers and said swingletrees.

4. In a draft-equalizer, in combination, an axle, a tongue attached thereto, a doubletree pivoted to said tongue, swingletrees, levers 30 pivoted at one end to each end of the doubletree, swivels pivoted to said levers at points nearest their outer ends and linked to said swingletrees, and swivel-hooks pivoted on the other ends of said levers, stay-chains adjustably connected between said swivel-hooks and said axle.

5. In a draft-equalizer, a vehicle, a movable member connected thereto adapted to have draft-animals attached thereto, levers 40 pivoted at one end to said movable member, and at the other end linked to said vehicle, and links for communicating the draft to desired points between the ends of said levers.

Signed at Waterloo, Iowa, this 9th day of 45 October, 1905.

JOHN W. HELTON.
